UNITED STATES PATENT OFFICE.

MORRIS MARCUS, OF NEW YORK, N. Y.

GARMENT-SUPPORTER.

SPECIFICATION forming part of Letters Patent No. 253,615, dated February 14, 1882.

Application filed December 19, 1881. (Model.)

To all whom it may concern:

Be it known that I, MORRIS MARCUS, of the city and State of New York, have invented an Improvement in Garment-Supporters, of which 5 the following is a specification.

Stocking-supporters have been made of a plate of metal having an opening therein which terminates at one end with a cross-bar, to which is attached a strap or elastic for suspending the 10 supporter, and at the other end the opening is narrow, terminating in the shape of a wedge. The garment is drawn into or partially through this opening, and the pull upon the stocking causes the fabric to pack tightly into the narrow 15 wedge-shaped opening. In use, however, it is discovered that the portion of the fabric coming into the narrowest part of the opening is the most tightly held, and consequently it is liable to take an undue strain and become 20 injured or cut against the edges of the metal of the supporter.

My invention is made for distributing the strain upon the fabric, so as to hold the same firmly within the supporter, and thus prevent 25 injury to the stocking or other garment.

In the drawings, Figure 1 is an elevation of the supporter and its strap or elastic. Fig. 2 is a view edgewise of the said supporter, and Fig. 3 is the metal plate forming the supporter 30 in larger size.

The elastic or strap *a* is connected to the cross-bar at one end of the supporter, which is made of a metal plate, *b*, having an opening, *c*, that tapers to the narrow nip at *d*, and 35 then spreads out into two branches, *e e*, that are at the edges of a convex finger, *i*, so that

the fabric which is drawn into the opening *c* passes down and is held at the nip *d*; but such fabric, when strained, will draw through the nip into the larger part of the opening below 40 the nip, and will rest upon the finger *i* and then spread into the branches *e e*, where it will again be nipped at the narrowest parts of these branch slots. Hence the fabric will be held at three places, the strain will not come upon 45 one part only, and the ends of the slots being wider than the nip portions, the fabric will pack in the wider end portions, and hence the hold will be upon a larger amount of the material than in the supporters heretofore constructed. 50

I am aware that a garment-supporter has been made with one or more tongues with sharp penetrating-points. These are liable to injure the fabric, because the strain comes principally 55 where the tongue penetrates the material. My improvement is for dispensing with penetrating-points or sharp-ended openings that injure the fabric.

I claim as my invention—

The garment-supporter composed of a plate with a main opening and two branch slots that pass at the edges of a round-ended finger, *i*, the ends of the slots being the widest, and there being three narrow places to nip and hold the 65 fabric, substantially as set forth.

Signed by me this 15th day of December, A. D. 1881.

MORRIS MARCUS.
